CLAIM

The ornamental design for a cuff with air delivery tube, as shown and described.

DESCRIPTION

FIG. 1 is a front perspective view of a cuff with air delivery tube according to an embodiment of our design;
FIG. 2 is a front view thereof;
FIG. 3 is a rear view thereof;
FIG. 4 is a top view thereof;
FIG. 5 is a bottom view thereof;
FIG. 6 is a left side view thereof;
FIG. 7 is a right side view thereof;
FIG. 8 is a reverse perspective view thereof;
FIG. 9 is a front perspective view of a cuff with air delivery tube according to an embodiment of our design;
FIG. 10 is a front view thereof;
FIG. 11 is a rear view thereof;
FIG. 12 is a top view thereof;
FIG. 13 is a bottom view thereof;
FIG. 14 is a left side view thereof;
FIG. 15 is a right side view thereof;
FIG. 16 is a reverse perspective view thereof;
FIG. 17 is a front perspective view of a cuff with air delivery tube according to an embodiment of our design;
FIG. 18 is a front view thereof;
FIG. 19 is a rear view thereof;
FIG. 20 is a top view thereof;
FIG. 21 is a bottom view thereof;
FIG. 22 is a left side view thereof;
FIG. 23 is a right side view thereof;
FIG. 24 is a reverse perspective view thereof;
FIG. 25 is a front perspective view of a cuff with air delivery tube according to an embodiment of our design;
FIG. 26 is a front view thereof;
FIG. 27 is a rear view thereof;
FIG. 28 is a top view thereof;
FIG. 29 is a bottom view thereof;
FIG. 30 is a reverse perspective view thereof;
FIG. 31 is a front perspective view of a cuff with air delivery tube according to an embodiment of our design;
FIG. 32 is a top view thereof;
FIG. 33 is a bottom view thereof;
FIG. 34 is a front view thereof;
FIG. 35 is a rear view thereof;
FIG. 36 is a right side view thereof;
FIG. 37 is a left side view thereof; and,
FIG. 38 is a reverse perspective view thereof.

The broken lines shown in FIGS. 1-6 and 8 represent environmental structure and do not form a part of the claimed design.
